ERNEST SANTIN, OF NEW YORK, N. Y.

Letters Patent No. 96,972, dated November 16, 1869.

TOY.

The Schedule referred to in these Letters Patent and making part of the same.

To all whom it may concern:

Be it known that I, ERNEST SANTIN, of the city, county, and State of New York, have invented a new and improved Toy; and I do hereby declare that the following is a full, clear, and exact description thereof, which will enable others skilled in the art to make and use the same, reference being had to the accompanying drawings, forming part of this specification.

Figure 1 represents a side elevation of my improved toy.

Figure 2 is a plan or top view of the same.

Similar letters of reference indicate corresponding parts.

This invention relates to a new toy of that class which is propelled by spring-power, and consists of an imitation velocipede, on which the jointed figure of a man or any other suitable figure is placed, and which receives motion by means of a spring, in such a manner that the wheels of the velocipede will be turned, and the extremities of the figure moved. Thereby a very amusing toy is produced, especially when the figures of animals, such as monkeys, dogs, &c., are placed upon the vehicle, so that their motion will correspond with those of the animals which they represent.

A, in the drawing, represents the front wheel or wheels,

B, the rear wheel or wheels of an imitation velocipede.

The axles of these wheels are hung in a frame, C, of suitable description and form.

The size of the imitation velocipede may vary from the smallest to nearly full size.

Its construction may be like that of the well-known French velocipedes, as illustrated in the drawings, or it may represent any other kind, with suitable other mechanism.

It is made of pasteboard, metal, wood, or other suitable material.

Upon its imitation seat D is fitted a wood, metal, pasteboard, or other figure, E, representing a man or other animal, with jointed extremities, as indicated in the drawing, which extremities are brought in contact and attached to those parts of the imitation velocipede which those of a living figure would reach, in order to control and occasion the motion of the machine.

A spring, F, of suitable kind, and to be wound up by suitable means, is arranged on the instrument, to set it in motion, whereby the wheels are turned, and the extremities of the figure moved.

In the drawing, an elastic cord is represented as the spring, and is fastened to the rear axle, around which it must be wound to set the instrument in motion; but any other kind of spring, fastened at any other place, may be used with equal advantage.

Having thus described my invention,
I claim as new, and desire to secure by Letters Patent—

As a new article of manufacture, the velocipede-toy herein described.

E. SANTIN.
